UNITED STATES PATENT OFFICE.

ALFRED C. EINSTEIN, OF ST. LOUIS, MISSOURI.

LIGHTING-FIXTURE.

1,161,119.

Specification of Letters Patent. Patented Nov. 23, 1915.

Application filed September 8, 1914. Serial No. 860,739.

To all whom it may concern:

Be it known that I, ALFRED C. EINSTEIN, a citizen of the United States, residing at St. Louis, Missouri, have invented a certain 5 new and useful Improvement in Lighting Fixtures, of which the following is a full, clear, and exact description, such as will enable others skilled in the art to which it appertains to make and use the same.

10 This invention relates to lighting fixtures and particularly to fixtures comprising reflectors for reflecting the light downwardly over a wide area.

One type of reflector that is used extensively with electric ceiling lights and with electric street lights is formed entirely of metal or some other suitable opaque material, and is so designed that it merely reflects the rays of light downwardly. One 15 objectionable feature of a lighting fixture provided with a reflector of the type referred to is that it throws a black shadow immediately above the reflector; and another objectionable feature is that a great 20 deal of light that could be used for illuminating or for advertising purposes is wasted.

One object of my invention is to provide a reflector for lighting fixtures that will throw the rays of light downwardly and distribute 25 the light over a wide area without causing a shadow to be formed immediately above the reflector.

Another object is to provide a lighting fixture that will produce an indirect light 30 below and above the fixture. And still another object is to provide a reflector for lighting fixtures which is so designed that practically all of the rays from the lighting unit are utilized.

35 Other objects and desirable features of my invention will be hereinafter pointed out.

Figure 1 of the drawings is a vertical sectional view of a lighting fixture constructed in accordance with my invention; Fig. 2 is 40 a detail view showing a different means from that illustrated in Fig. 1 for fastening the parts of the reflector of the fixture together; and Fig. 3 is a vertical sectional view illustrating another form of my invention.

I have herein illustrated my invention as 45 embodied in a fixture designed for use with a large incandescent light unit, but it will, of course, be understood that the particular lighting means with which the fixture is

used is immaterial so far as my invention is concerned.

Referring to Fig. 1 of the drawings, A designates a large incandescent light bulb that is mounted in a socket B, and 1 and 2 50 designate the two parts of the reflector of my improved fixture. The part 1, which I will term the reflecting member, is preferably formed of metal and is coated with porcelain, enamel or some other substance 55 that produces a brilliant reflecting surface. The part 2, which I will term the transparent member, is formed of glass or some other suitable material that is transparent or translucent so that the rays of light from 60 the bulb A can pass through same, the term "transparent" being herein used to mean a substance or part that is perfectly transparent or only translucent.

In the form of my invention shown in 65 Fig. 1 the transparent portion 2 of the reflector is substantially cylindrical-shaped and projects upwardly from the opaque reflecting member 1 which flares downwardly and outwardly from the lower end of the portion 2. A cap 3 which is preferably 70 formed of metal and provided with ventilating openings 4 is connected to the upper end of the cylindrical-shaped portion 2 of the reflector, the means 5 that supports the 75 reflector being secured to said cap. It is immaterial, so far as my broad idea is concerned, how the cylindrical-shaped transparent portion 2 is fastened to the cap 3 and to the flared reflecting member 1. In the form 80 of my invention shown in Fig. 1 the portion 2 is provided at its opposite ends with screw-threads 6 that coöperate with internal screw-threads on flanges 3^a and 1^a on the cap 85 3 and on the reflecting member 1, respectively, and in the form of my invention 90 illustrated in Fig. 2 the flanges on said cap and reflecting member are provided with set screws 6^a that coöperate with lips 7 on the opposite ends of the cylindrical-shaped portion 2. The rays of light from the lighting 95 means are thrown downwardly and distributed over a wide area by the opaque reflecting member 1, and some of the rays from said lighting means pass upwardly and laterally through the transparent or translucent portion 2, thereby preventing a shadow 100 from being cast immediately above the reflector by the opaque portion 1. In order 105 that an indirect light will be produced I use 110

an electric light bulb A whose under side 8 is frosted or coated with a substance that acts as a diffusing shield which tends to dim the rays and give an opalescent effect, therefore causing the rays to be reflected onto the reflecting member 1 and also upwardly through the transparent portion 2.

When a reflector of the construction above described is used with a ceiling light the ceiling immediately above the reflector will be illuminated by the rays of light that are thrown outwardly and upwardly through the transparent portion 2, and the reflecting member 1 will diffuse the light over a wide area. Consequently, such a lighting fixture produces an indirect light above and below the lighting unit and does not cast a large black shadow on the ceiling. When the reflector is used with a street light, the transparent or translucent portion 2 can be provided with letters or characters so as to form an advertising medium, thereby causing all of the light from the lighting unit to be utilized.

Still another desirable feature of such a fixture is that it will produce two different colored lights if the transparent portion 2 of the reflector is formed from glass or other suitable transparent or translucent material of a different color or hue from the glass of the electric light bulb A, thereby making the fixture particularly well adapted for a street light that is used to indicate the location of a certain object such, for example, as a fire-alarm box.

The reflector of the fixture shown in Fig. 3 is not provided with a cylindrical-shaped portion 2 for receiving the lamp socket, but is approximately inverted cone-shaped and comprises a transparent or translucent upper portion 20 and an opaque lower portion or reflecting member 10, said portions being connected together in some suitable manner, as, for example, by means of rings 45 or flanges 11 at the upper end of the reflecting member 10 that embrace the lower end of the transparent portion 20. A cap 30 provided with ventilating openings 4^a is connected to the upper end of the transparent portion 20, and chains or some other suitable supporting means 5^a are connected to the reflecting member 10 so as to sustain the reflector. Instead of using an electric light bulb provided with a frosted lower portion, as shown in Fig. 1, a diffusing shield 8^a, preferably formed of translucent material, is arranged under the lighting means so as to produce an opalescent effect and reflect the rays upwardly against the under-side of the reflecting member and through the transparent upper portion 20, the shield 8^a shown in Fig. 3 being suspended from the reflecting member 10 by means of chains 12 or other suitable devices.

While I prefer to form the reflector partly from metal or some other suitable opaque material and partly from a substance that is transparent or translucent, I do not wish it to be understood that my invention is limited to such a construction, for the novel feature of my improved reflector is that it has an opaque portion that reflects the light downwardly and a transparent or translucent upper portion through which the rays can escape so as to produce a light above the opaque portion of the reflector. Therefore, it would be possible to form the entire reflector from transparent or translucent material and coat the lower portion with a substance that would render it opaque.

In addition to the desirable features above mentioned, my improved fixture presents a neat and ornamental appearance, it is strong and serviceable, it is inexpensive to manufacture, it enables all of the rays from the lighting unit to be utilized, and it produces an indirect light above and below the fixture.

Having thus described my invention, what I claim as new and desire to secure by Letters Patent is:

1. A light reflector having a frusto-conical-shaped opaque portion that reflects the light downwardly and a transparent or translucent portion arranged at the center of said opaque portion above the lighting unit through which the light escapes and lights the space above said opaque portion; and means arranged under the source of light which reflects the rays upwardly against said opaque portion and through said translucent portion.

2. A lighting fixture comprising a reflector provided with a frusto-conical-shaped opaque portion designed in such a manner that it reflects the light from the lighting means downwardly, a cylindrical-shaped transparent center portion arranged above the lighting means and up through which the rays pass, and a translucent diffusing shield of less diameter than said opaque portion arranged under the lighting means.

3. An electric light reflector comprising a downwardly flared opaque reflecting member, a ventilated cap, and a transparent or translucent member arranged intermediate said cap and reflecting member and connected to same so as to serve as a supporting means for said reflecting member.

4. A lighting device comprising an electric lighting unit, a downwardly inclined reflecting member surrounding said unit, a ventilated cap arranged above said unit, a transparent or translucent member arranged intermediate said cap and reflecting member and serving to connect said parts together, and means for causing the rays

from said lighting unit to be reflected onto the under-side of said reflecting member and through said transparent portion.

5. An electric light reflector comprising a metallic reflecting member which flares downwardly and outwardly from the source of light, a metal cap provided with ventilating openings, and a cylindrical-shaped transparent or translucent member 10 ranged between said cap and reflecting

member and detachably connected to same, so as to serve as a supporting means for said reflecting member.

In testimony whereof I hereunto affix my signature in the presence of two witnesses, 15 this third day of September, 1914.

ALFRED C. EINSTEIN.
